CYLINDER HEAD FOR INTERNAL COMBUSTION ENGINES

Application filed December 26, 1930, Serial No. 504,688, and in Switzerland May 26, 1930.

This invention relates to cylinder heads or covers for internal combustion engines, and more particularly for double-acting engines, of the kind in which the head or cover is provided with a central opening which is surrounded by an annular water chamber and accommodates for example a piston rod, and with one or more other openings or sockets for valves, the cylinder head or cover being 10 clamped to the cylinder by a clamping ring through holes in which pass retaining bolts connecting the ring to the cylinder.

In existing cylinder heads of this kind, since the clamping ring lies partly within the 15 ring of retaining bolts, the diameter of the outer circumferential wall of the cylinder head which is surrounded by the clamping ring is limited, with the result that the walls of the sockets for the valves which, owing to 20 the central opening, are of necessity each arranged eccentrically with respect to the cylinder axis, pass into the outer circumferential wall of the cylinder head throughout their length so that the cooling water space cannot 25 not completely surround these sockets and it is thus impossible to obtain adequate cooling thereof.

A cylinder head according to the present invention for an internal combustion engine 30 of the kind referred to above comprises in combination with the clamping ring through which pass the retaining bolts, a water-cooled cylinder head or cover having an annular water chamber a part of the outer circumferential wall of which remote from the cylinder is surrounded by the clamping ring while a part adjacent to the cylinder is of 35 larger diameter so as to lie adjacent to the retaining bolts and form a shoulder on which 40 the clamping ring bears, this enlarged part of the circumferential wall of the annular water chamber being provided with a radially projecting portion extending between the 45 retaining bolts adjacent to each valve socket

so as to increase the water space around the sockets.

One construction according to this invention is illustrated by way of example in the accompanying drawings, in which

Figure 1 is a section on the line I—I of Figure 2, and

Figure 2 is a section on the line II—II of Figure 1.

In the construction illustrated the cylinder 55 head comprises a body portion *a* provided with an opening *b* for a piston rod and with sockets *c* for fuel injection valves which pass through the annular water cooling chamber *d* surrounding the central opening *b*.

A clamping ring *e*, through which pass securing bolts *f*, is provided for clamping the cylinder head *a* to the cylinder and, according to this invention, the clamping ring surrounds only a part of the cylinder head *a* 60 lying remote from the cylinder. The outer circumferential wall of the part of the cylinder head *a* which lies adjacent to the cylinder is of larger diameter than that surrounded by the clamping ring *e* so that it lies adjacent to 65 the retaining bolts *f* and forms a shoulder on which bears the clamping ring. Further, this enlarged part of the circumferential wall of the cylinder head *a* is provided with protruding portions in the neighborhood of each of 70 the valve sockets *c* so as to increase the width 75 of the cooling chamber around these sockets.

Water is delivered to the cooling chamber *d* through a pipe *g* the outlet end of which is conveniently bent so that the water is delivered substantially tangentially with respect to the cooling chamber so as to cause the water in this chamber to circulate in the direction of the arrows and thus increase its 80 cooling action.

I claim:

In an internal combustion engine the combination with a clamping ring with holes for introducing retaining bolts, of a water-cooled cylinder head having an annular water cham- 90

ber a part of the circumferential wall of which remote from the cylinder being surrounded by the clamping ring while a part of this wall adjacent to the cylinder being enlarged in diameter so as to lie adjacent to the retaining bolts and form a shoulder on which the retaining ring bears, this enlarged part of the circumferential wall being provided with a protruding portion extending between the retaining bolts adjacent to each valve socket so as to increase the water space around such sockets.

10

In testimony whereof I have affixed my signature.
